UNITED STATES PATENT OFFICE.

HORATIO G. LANE, OF WHITEHALL, NEW YORK.

METHOD FOR FORMATION AND STORAGE OF ICE.

Application filed March 21, 1922. Serial No. 545,511.

To all whom it may concern:

Be it known that I, HORATIO G. LANE, a citizen of the United States, residing at Whitehall, in the county of Washington and State of New York, have invented certain new and useful Improvements in Methods for Formation and Storage of Ice, of which the following is a specification.

This invention relates to an improved method of forming ice for storage.

The primary object of the invention is the provision of an improved method for forming ice in relatively large quantities, either in a house directly adapted for storage of the same, or at a convenient location, thus doing away with the expensive and cumbersome method of ice collecting incident to the salvaging of ice, from ponds, rivers, and streams, where it is first necessary to cut the ice, haul the same, and finally store the same.

A further object of the invention is the provision of an improved means for forming ice in large masses in an atmosphere of freezing temperature.

A further object of the invention is the provision of an improved method for the formation of huge masses of ice, for storage purposes, this ice being preferably so formed that the same can be conveniently disassembled and taken out of storage for use.

A further object of the invention is the provision of inexpensive and simple apparatus for the formation of relatively great quantities of ice.

A further object of the invention is the provision of an improved method of ice formation, whereby water of a desired purity may be taken from a spring or other source, for the formation of ice in great quantities.

Other objects and advantages will be apparent during the course of the following detailed description.

In the accompanying drawings, forming a part of this specification, and wherein similar reference characters designate corresponding parts throughout the several views.

Figure 1 is a cross sectional view of the apparatus used in connection with the formation of ice under the improved method.

Figure 2 is a cross sectional view taken through the apparatus illustrated in Figure

1 and showing the manner in which a layer of ice is formed therein.

Figure 3 is a cross sectional view showing the manner in which the apparatus is regulated with respect to the layer of ice formed therein, as illustrated in Figure 2, and showing the apparatus in position for the formation of an additional layer of ice.

Figures 4, 5, and 6 show the improved apparatus as illustrated in Figure 3, additionally showing successive steps in preparing the layer of ice for the superposing of an additional layer of ice.

Figure 7 is a cross sectional view, showing the manner in which a second layer of ice is disposed upon the layer of ice first formed within the apparatus.

Figure 8 is a horizontal cross sectional view, taken on a plane intermediate the layers of ice, showing the manner in which an upper layer is supported upon and spaced from a lower layer of ice.

In the drawings, wherein for the purpose of illustration is shown the preferred embodiment of my invention, the numeral 10 designates an apparatus for the formation of ice, including a plurality of corner posts or standards 11 of any desired height, consistent with the height to which the ice is to be formed. Side walls 12 and 13, and end walls 14 and 15 may be provided, formed of planks or any approved material, which are appropriately affixed to the corner posts or standards 11, so that an enclosure 15 is provided, preferably of rectangular formation, to define the dimensions to which the ice is to be formed. It is preferred that the planks or materials forming the side and end walls be all of the same height; one of the walls, such as the side wall 13 having an opening or slot 17 therein, provided for a purpose which will be subsequently set forth.

As illustrated in Figure 1, the apparatus 10 is assembled upon the ground surface, so that the same may receive a body of water, either by spraying or by pouring the same therein, in order to freeze a layer of ice. The opening or slot 17 is, of course, plugged during the formation of this layer of ice, as by wet snow or other means 17a. The ice so formed, is of a predetermined thickness as determined by the height of the walls of the apparatus 10 so that a base layer 20 is formed, having a relatively even upper surface 21. This layer of ice 20, may, of course,

be of a thickness so that the top surface 21 lies below the upper marginal edges 22 of the apparatus 10.

Since the ice to be formed by this improved method will sometimes reach the height of many feet, it is desired that the layer 20 be of such thickness that the apparatus 10 may be conveniently handled by a minimum number of persons. The layer 10 of ice 20, is likewise of such thickness that the same may be conveniently handled when cut into blocks. The next step in the formation of the ice for storage purposes, is that of raising the side and end walls, 12 to 15 inclusive, upwardly upon the supporting standards 11, as is illustrated in Figure 3 of the drawings, so that the lower marginal edges of said walls are raised off of the ground surface and lie just below the 20 top surface 21 of the already formed layer of ice 20. In this position, the walls of the apparatus 10 provide an enclosure for the further formation of an additional layer of ice, superposed upon the basic layer 20.

It will be desirable that the superposed 25 layers of ice be separated from each other, so that the facing surfaces of said layers do not coalesce. To this end, after the walls of the apparatus 10 have been raised, as is 30 illustrated in Figure 3, a very thin layer of water, in depth a quarter or half inch is flooded upon the top surface 21 of the base layer 20, and while the water is in its fluid state, the spacing members 23 are disposed 35 upon the surface 21 of the layer 20, so that as this relatively shallow body of water freezes upon the upper surface 21, the spacing members 23 will be bound in secure position upon the layer 20, in the position illustrated in Figure 4. Of course, the members 40 23 extend upwardly above the shallow body of water which binds them to the layer 20. These members 23 are preferably pieces of ice and of the same height. After the spacing members 23 has been bonded to the base 45 layer of ice 20 as above described, the enclosure defined by the walls 12, 13, 14 and 15 is flooded with water, to a height just above the piers 23, and as illustrated in Figure 5, of the drawings. It is to be observed 50 that this body of water 25, cannot escape through the opening 17 in the apparatus wall 13, nor through any marginal cracks or crevices about the top of the layer of ice 20, due to the fact that wet snow or other 55 material 26 has been placed as to seal the openings and apertures, as is clearly illustrated in Figure 3 of the drawings. The body of water 25, of course, freezes from the 60 top, and when the same is frozen to a point just below the top or upper surfaces of the spacing piers or members 23, and before the same is entirely frozen to the upper surface 21 of the base layer 20, the seal provided 65 by the wet snow 26 is removed from the

opening 17 in the form 10, so that the residue water may be drained from the space 28 intermediate the top or auxiliary layer of ice 29, which rests upon the piers 23, and the base layer 20. Of course, due to the 70 fact that this auxiliary layer 29 is frozen to a depth below the upper parts of the piers 23, it can readily be understood that the same has established a bond with the piers 23. Likewise, the body of water 25 75 will freeze inwardly from the marginal edges thereof, about the walls of the apparatus 10, to provide marginal portions 29^a, frozen between the layer 20 and the auxiliary layer 29, and in this respect cooperating 80 with the supporting piers 23, which are now frozen solidly to the layers 20 and 29, and substantially as is illustrated in Figure 6 of the drawings.

After the draining of the water from the space 28, it can readily be seen that the layers 20 and 29 are separated from each other, by an air space 28, except for the piers 23 and the marginal portions 29^a. To prevent the body of water 25 from freezing 90 solid to the top of the base layer 20, a vent aperture or opening 31 is punched or drilled through the auxiliary layer 29 after the same has formed to a depth below the tops of the supporting members 23, and by insertion of a person's finger or a rod, the depth of the water in the space may be gaged, for determining that the body 25 is not frozen solid. As the water flows from 95 the space 28 outwardly through the drain opening 17 provided in the wall 13, it is obvious that the vent aperture or opening 31, serves a useful purpose, in that air may be supplied therethrough to the space 28 to permit outflow of the water therefrom. 100 The water which exits from the opening 17 need not be wasted, since in many instances the water of which the ice is formed will be spring water, and of unusual purity. To prevent the wasting of this water from the space 28, a suitable pumping apparatus may be provided adjacent the main opening 17 for collecting the same. After the water has all been drained from the air space 28 intermediate the base layer 20 and the auxiliary layer 29 spaced therefrom, a plug 110 35 of wet snow or similar material, may be disposed in the drain opening 17, in order that the air space 28, intermediate the base layer 20 and the auxiliary layer 29, may be entirely sealed and closed to prevent access 115 of any water thereto. After this operation, water may be sprayed or poured upon the top of the auxiliary layer 29, so that a layer 37 is formed directly over the base layer 20, it, of course, being understood that this layer 37 includes the auxiliary layer 29 and the water disposed thereover which augments therewith. The layer 37 is preferably 120 of the same thickness as the base layer 20. 125 130

The next operation will be that of again raising the walls of the apparatus 10 substantially as in the manner above described, for attachment upwardly of the standards 5 or supports 11, and the provision of air spaces intermediate successive layers is formed in the above described manner. By this method, any number of the additional layers 37 may be provided upon the bottom 10 layer 20 to provide a huge mass of ice, of many feet in height.

From the foregoing, it can be seen that a method of forming huge bodies of ice has been perfected, by the superpositioning 15 of a plurality of layers, with air spaces intermediate adjacent layers. By this arrangement, no impure spacing arrangements intermediate the layers is provided, such as paper and other separating expedients, and which ordinarily would lessen the purity of the resulting body of ice. In fact, nothing is interposed in the resulting body of ice, except the pure water ingredient, of which the same is composed.

25 The ice may be formed in any approved storage house or frame work provided therefor, and insulated in any of the well known ways.

While the formation of ice after the 30 method herein described is preferably carried on during the winter months, and in an atmosphere of freezing temperature, yet ice may be formed after the process herein described in an atmosphere the temperature of which is lowered to the freezing point and below the same by artificial means.

From the foregoing, it is to be observed 35 that a huge and compact body of ice may be formed by a single person following the above method. It is at once obvious that such a method of ice formation is more compact and less expensive than the method of storing ice in use at the present time. When desiring to use ice from the huge 40 body an operator may start with the top layer of ice and extract pieces therefrom, due to the manner in which the layers are spaced from each other. In this manner, it can be seen that the successive layers of 45 ice may be consumed in order, and without unnecessary mutilation thereof.

Various changes in the shape, size and arrangement of parts of the improved apparatus, may be made in order to conform 50 to the method set forth in this specification and defined in the claims.

I claim:

1. That method of forming ice in an atmosphere of freezing temperature, which 55 consists in forming a layer of ice, placing supports upon the top of said layer, flowing water over said supports and allowing the top surface of said water to freeze to form a second layer of ice until the upper parts

of the supports are frozen in said second layer, and draining the remaining water just upwardly of said first mentioned layer from intermediate said layers to provide an air space.

2. That method of forming ice in an atmosphere of freezing temperature, which 60 consists in the forming of a base layer of ice, placing supports upon the top of said layer, flowing water on top of said layer to a level just above the tops of said supports, 65 permitting the top part of the body of water above said base layer to freeze to a point below the top of said supports and whereby said supports are partially encased in an auxiliary layer of ice formed at the top of 70 said body of water, draining the residue water from between said auxiliary layer and the base layer, and augmenting the thickness of said auxiliary layer of ice by flowing water thereon and permitting it to freeze. 85

3. That method of forming ice in an atmosphere of freezing temperature, which 90 consists in the formation of a layer of ice of determined thickness, flowing a thin film of water upon said layer of ice, depositing spaced supporting members upon said thin 95 film of water and permitting the same to be bonded with said layer of ice by freezing of said film of water, providing a second layer of ice upon said first mentioned layer of ice 100 by flooding a body of water upwardly thereon and permitting the same to freeze to a depth just above and spaced from the top of said first layer of ice, sufficiently to encase the upper portions of said supporting members, and draining the residue of water from intermediate said layers of ice to provide a space therebetween. 105

4. That method of forming ice in an atmosphere of freezing temperature, which 110 consists in the formation of a layer of ice, flooding the surface thereof to provide a film of water thereon, disposing supporting members upon said surface so that the film of water when frozen will bind said supporting members to said layer, again flooding the surface of said layer with a body of water to cover said supporting members, permitting said body of water to freeze to a depth just below the tops of said supporting members to a point just above the top of said first mentioned layer of ice to provide an auxiliary layer of ice supported by said supporting members, permitting the water intermediate said first mentioned layer of 115 ice and said auxiliary layer to drain to provide an air space intermediate said first mentioned layer of ice and said auxiliary layer of ice, and augmenting the auxiliary layer of ice to provide a second layer of ice of a 120 required thickness. 125
